UNITED STATES PATENT OFFICE.

JACOB HENRY POSTEL, OF SAN MATEO, CALIFORNIA.

FOUNTAIN BRUSH.

Application filed July 8, 1922. Serial No. 573,526.

To all whom it may concern:

Be it known that I, JACOB H. POSTEL, a citizen of the United States, residing at San Mateo, in the county of San Mateo and State 5 of California, have invented a new and useful Fountain Brush, of which the following is a specification.

This invention relates to brushes and more particularly to fountain brushes.

10 The object of the invention is to provide a brush of this character so constructed that the head may be readily removed for cleaning, repairs, or for the substitution of another head.

15 Another object is to provide a brush head so constructed as to facilitate the removal of dirt from under vehicle fenders, between the spokes of the wheels and from other places ordinarily not easily accessible.

20 Another object is to provide a brush head holder equipped with releasable head engaging means for effecting a water tight connection between it and the head without interfering with the flow of water to the 25 head.

Another object is to provide a simple and efficient connector for the head and the holder of a brush which presents no obstruction on the back such as would be liable to 30 mar the finish of the car or other object being cleaned with the brush.

With the foregoing and other objects in view which will appear as the description proceeds, the invention resides in the combination and arrangement of parts and in the details of construction hereinafter described and claimed it being understood that changes in the precise embodiment of the invention herein disclosed may be made within the 35 scope of what is claimed without departing from the spirit of the invention.

In the accompanying drawings:—

Figure 1 represents a side elevation of a brush constructed in accordance with this invention shown applied to a hose nozzle.

Fig. 2 is a longitudinal section thereof, and

Fig. 3 is a transverse section taken on the line 3—3 of Fig. 1.

50 In the embodiment illustrated, a holder 1 for the brush head 20 is shown constructed preferably of aluminum and of a shape and size to conform to that of the head 20. This casing 1 has an upright or rectilinear rear end wall 3 and a downwardly and forwardly inclined front wall having an inturned lip

4 at its lower end which is designed to engage the front end of the lower face of the brush head 20 as is shown clearly in Fig. 2 to operate in connection with a fastener 15 hereinafter to be described for holding the head in the casing.

A backing 5 preferably of rubber is located in the casing 1 against the upper wall thereof and is provided with a plurality of openings 6 which register with apertures 7 in the upper wall of the casing 1 and with similar apertures 21 extending from face to face of the brush head 20 and discharging into the bristles 22 of said head. These apertures 7 also register with similar apertures 8 formed in a tubular handle 10, the front end of which is mounted on the upper wall of the casing 1 and fixedly connected thereto either by soldering or by being made integral therewith. The front end of the tubular member 10 is inclined to correspond with the inclined end 3 of the casing 1 as is shown clearly in Fig. 2.

The brush head 20 has its front end inclined to correspond with the inclined end 3 of the casing 1 and the bristles 22 at said end are also inclined correspondingly as is shown clearly in Figs. 1 and 2, said projecting bristles being designed to enter corners to facilitate the removal of dirt therefrom.

The tubular handle 10 has its rear end threaded as shown at 11 for connection with the internally threaded end of a hose nozzle H. This threaded handle end is plugged as 90 shown at 12, and the side walls of said handle are provided with a plurality of apertures 13 spaced longitudinally apart and designed for controlling the amount of water supplied through the handle 10 to the brush head.

A wing nut 14 is mounted on the threaded portion of the handle and carries a rubber washer or gasket 14^a which is designed to abut the end of the nozzle H after the handle has been screwed into said nozzle and to form a water tight connection between them and also lock the handle engaged with the nozzle.

Mounted on the handle 10 is a brush head fastener 15 here shown constructed of heavy wire made substantially U-shaped in form with the free ends of the legs thereof pivotally engaged with the opposed faces of the handle 10. The legs of this U-shaped fastener are provided intermediate their ends at points adjacent the rear end wall of the

casing 1 with laterally extending loops 16 which form bearings for a bail shaped hook, the bill 19 of which is designed to engage the lower face of the rear end of the brush head 20 as shown clearly in Fig. 2 to cooperate with the lip 4 of the casing 1 holding said head operatively connected with the casing.

The cross bar 17 of the fastener 15 is shown 10 inclined outwardly and is designed to straddle the handle 10 and to snugly fit against the inner face thereof when the parts are in locking position, thereby securely holding the hook 18 engaged with the brush head.

15 When it is desired to release the brush head from the casing, the cross bar 17 is forced outwardly thereby releasing the hook 18 from the head, permitting the head to be slipped out of the casing for any purpose 20 desired.

From the above description it will be obvious that the head 20 may be removed and any other head carrying bristles of different character may be substituted adapting the 25 device for use for various purposes.

The threaded end of the tubular handle 10 is of a size to engage any standard pipe thread to permit said handle to be attached to the ordinary garden hose. This threaded 30 handle portion may be turned or screwed into the nozzle H to cause the plugged end of the handle to be forced against the valve seat in the nozzle thereby controlling the amount of water supplied through the nozzle. The apertures 13 formed in the threaded 35 end of the handle 10 also assist in con-

trolling the amount of water supplied through the handle to the head, one or more of said openings being closed by the threaded nozzle end when desired as is shown 40 clearly in Fig. 2, and which may be locked in this position by tightening up the wing nut 14.

The head 20 is provided on its lower face 45 at its rear end with a stud 23 with which is designed to be engaged the bill 19 of the hook or catch 18 when in operative position to assist in retaining the catch against accidental release.

I claim:—

In a brush of the class described a shell-like casing having a water supply chamber mounted thereon with registering apertures between them, a brush head mounted in said casing, a fastener mounted on said chamber and composed of heavy wire U-shaped in form with the free ends of the legs thereof engaged with the opposed faces of said chamber, said legs being provided intermediate their ends with laterally extending depending loops, and a bail-shaped hook carried by said loops and adapted to engage the brush head, and means cooperating with said hook to hold the head in the casing.

In testimony that I claim the foregoing as 65 my own, I have hereto affixed my signature in the presence of two witnesses.

JACOB HENRY POSTEL.
